ATTORNEY.

UNITED STATES PATENT OFFICE.

JOSEPH H. MASLAND, OF PHILADELPHIA, PENNSYLVANIA.

SPRING FOR PILLOWS, CUSHIONS, &c.

SPECIFICATION forming part of Letters Patent No. 691,065, dated January 14, 1902.

Application filed September 24, 1901. Serial No. 76,343. (No model.)

To all whom it may concern:

Be it known that I, JOSEPH H. MASLAND, a citizen of the United States, residing at Philadelphia, in the county of Philadelphia and 5 State of Pennsylvania, have invented certain new and useful Improvements in Springs for Pillows, Cushions, &c., of which the following is a specification.

My invention relates to improvements in 10 springs for pillows, cushions, and similar articles for use or ornament, possessing lightness of weight, great elasticity, coolness, and thorough ventilation. These springs may be used in pillows or cushions for hammocks, 15 beds, sofas, or couches, and for any similar purpose wherever pillows or cushions are desirable—in fact, wherever small weight, elasticity, and coolness are desiderata.

A cool well-ventilated pillow for use on a 20 hammock, which can easily be detached for use on couch or bed or for the purpose of cleaning the cover, is desired, and this object 25 I have attained by my invention.

By this invention I secure a pillow or cushion 30 having a great degree of elasticity or resiliency and at the same time not only a head-rest, but by reason of the lateral coils I secure a support for the neck and shoulders, which adds greatly to the comfort of the user and 35 the usefulness of the pillow or cushion.

My invention consists of a spring for pillows or cushions formed of a section of woven, 40 plaited, or braided wire folded into two parts, so that when the opposite sides of the folded 45 piece are turned under and coiled toward one another in opposite directions in one or more convolutions the top is separated from the bottom and a pocket is formed, into which I insert and attach thereto as many spiral

40 springs as may be necessary to increase the

degree of elasticity or resiliency secured by

the lateral coils.

These springs may be of any size or shape

and may be covered with fabric of any de-

45 gree of fineness.

By means of this spring I obviate the use of any other kind of filling for the pillow and secure a better and more healthful head-rest than ordinarily has been in use, especially on hammocks.

Referring to the accompanying drawings, 50 Figure 1 represents a piece of woven-wire cloth. Fig. 2 is a perspective view of the wire spring. Fig. 3 is a section of the spring cut at right angles across the coils.

Like letters refer to like parts.

In Fig. 1, A represents a piece or section of woven wire ready to be folded into two parts prior to rolling or coiling the ends thereof 55 into a spring.

In Fig. 2, A A represent the woven-wire curved top or body and the material of the coils of the spring, which extend on both sides thereof throughout its whole length. B B represent the coils on each side of the body. 60 C C represent the spiral springs inserted into the spring-pocket D D.

In Fig. 3 is shown an end view of a section of the spring, in which A is the material composing the body of the spring. B B represent 65 the coils or convolutions of the top extending along both sides of and under the body. D D represent the pocket formed by coiling the material composing the body and coils, and C indicates the spiral spring inserted into 70 this pocket.

I claim as my invention—

A pillow or cushion spring of woven wire having a pocket formed by folding the woven wire into two sections, and coiling or rolling 80 the opposite edges of the doubled wire into convolutions, with spiral springs inserted in the pocket, substantially as and for the purpose described.

JOSEPH H. MASLAND.
